US00D829192S

(12) **United States Design Patent** (10) Patent No.: **US D829,192 S**
(45) Date of Patent: **** Sep. 25, 2018**

(54) **PORTABLE WIRELESS SPEAKER**

(71) Applicant: **Shenzhen Pangshi Technology Co., Ltd.**, Shenzhen, Guangdong (CN)

(72) Inventor: **Futang Liu**, Guangdong (CN)

(73) Assignee: **Shenzhen Pangshi Technology Co., Ltd.**, Shenzhen (CN)

(**) Term: **15 Years**

(21) Appl. No.: **29/601,881**

(22) Filed: **Apr. 26, 2017**

(51) LOC (11) Cl. **14-03**

(52) U.S. Cl.

USPC **D14/216**

(57) **CLAIM**

The ornamental design for a portable wireless speaker, as shown and described.

DESCRIPTION

FIG. 1 is a first perspective view of a portable wireless speaker showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the portable wireless speaker which form no part of the claimed design.

1 Claim, 8 Drawing Sheets

FIG. 1

FIG. 2

FIG. 3

FIG. 4

FIG. 5

FIG. 6

FIG. 7

FIG. 8
